(57) **CLAIM**

The ornamental design for a personal massager, as shown and described.

DESCRIPTION

FIG. 1 is a top perspective view of a first embodiment of a personal massager according to the present design.

FIG. 2 is a bottom perspective view of the personal massager shown in FIG. 1.

FIG. 3 is a front elevation view of the personal massager shown in FIG. 1.

FIG. 4 is a rear elevation view of the personal massager shown in FIG. 1.

FIG. 5 is a top plan view of the personal massager shown in FIG. 1.

FIG. 6 is a bottom plan view of the personal massager shown in FIG. 1.

FIG. 7 is a left side elevation view of the personal massager shown in FIG. 1.

FIG. 8 is a right side elevation view of the personal massager shown in FIG. 1.

FIG. 9 is a top perspective view of a second embodiment of a personal massager according to the present design.

FIG. 10 is a bottom perspective view of the personal massager shown in FIG. 9.

FIG. 11 is a front elevation view of the personal massager shown in FIG. 9.

FIG. 12 is a rear elevation view of the personal massager shown in FIG. 9.

FIG. 13 is a top plan view of the personal massager shown in FIG. 9.

FIG. 14 is a bottom plan view of the personal massager shown in FIG. 9.

FIG. 15 is a left side elevation view of the personal massager shown in FIG. 9; and,

FIG. 16 is a right side elevation view of the personal massager shown in FIG. 9.

The broken lines depict portions of the personal massager that form no part of the claimed design. The dot-dashed
